(57) **CLAIM**

The ornamental design for a combined speaker and amplifier, as shown and described.

DESCRIPTION

FIG. 1 is a right front side perspective view of a combined speaker and amplifier showing my design;

FIG. 2 is a right rear bottom side perspective view of the combined speaker and amplifier as shown in FIG. 1;

FIG. 3 is a front elevational view of the combined speaker and amplifier as shown in FIG. 1;

FIG. 4 is a rear elevational view of the combined speaker and amplifier as shown in FIG. 1;

FIG. 5 is a left side elevational view of the combined speaker and amplifier as shown in FIG. 1;

FIG. 6 is a right side elevational view of the combined speaker and amplifier as shown in FIG. 1;

FIG. 7 is a top plan view of the combined speaker and amplifier as shown in FIG. 1; and,

FIG. 8 is a bottom plan view of the combined speaker and amplifier as shown in FIG. 1.

The broken lines environmental are for illustrative purpose only and form no part of the claimed design.
